Inventor:

Max Buch,
by Spear Middleton, Daniels in Spear
Atty's

UNITED STATES PATENT OFFICE.

MAX BUCH, OF DETROIT, MICHIGAN, ASSIGNOR TO HENRY E. EDWARDS, OF JACKSON, MICHIGAN.

TOP FOR VEHICLES AND THE LIKE.

1,290,069

Specification of Letters Patent.

Patented Jan. 7, 1919.

Application filed October 22, 1917. Serial No. 197,837.

To all whom it may concern:

Be it known that I, MAX BUCH, a subject of the Emperor of Germany, and resident of Detroit, Michigan, have invented certain new and useful Improvements in Tops for Vehicles and the like, of which the following is a specification.

My invention relates to improvements in tops for motor vehicles and the like and 10 aims to provide an extremely simple and economical top, which shall be self-supporting during its folding and projecting movements, thus enabling it to be operated easily by a single individual, and the folds of the 15 covering material to be properly arranged.

The invention also aims to provide a construction in which the liability of damage to the covering material in the closed position of the top will be reduced to a minimum.

With these and other objects in view, the invention includes the novel features of construction and arrangement and combination of parts hereinafter described, my said invention being defined by the appended claims.

An embodiment of my invention is illustrated in the accompanying drawing, in which,

30 Figure 1 shows the top as applied to a motor vehicle, the parts being shown in extended position in full lines and in partially folded position in dotted lines.

Fig. 2 is a view of a modification.

35 In this drawing, the top being shown in side elevation, only the standard, bow arms, etc., on one side appear, but it will be understood that they are duplicated on the other side, one side only being shown for convenience. Similarly in the following description and claims when reference is made to a bow arm or member it refers to one side only and is to be considered as covering by implication the duplicate parts on the other side.

40 In this drawing and referring first to Fig. 1 the numeral 1 designates the body of the vehicle for which the top is adapted and which is intended to be representative of any type of vehicle or motor boat requiring such a protective covering. The top covering material is indicated at 2, supported by the folding frame, which comprises the following parts.

45 3 designates a main standard adapted to

have its lower end pivotally connected with the body of the conveyance, as indicated at 3^a, and 4 designates the usual pivoted rear bow arm.

The main standard, in the unfolded position of the top, is arranged to incline forwardly at approximately the angle shown.

The outrigger bow arm is shown at 5 and is supported from the standard by a link or member 6, which is pivotally connected to 65 the outrigger bow arm by preferably a lock joint 5^a, and to the standard 3 by a pivot 6^a. A cover supporting bow arm 7 is pivotally connected to the standard 3 at 7^a, and the link or member 6 has a part 6^b projected 70 rearwardly of its pivot 6^a and connected directly to the bow arm 7 by a pin and slot connection 7^b.

By this arrangement when the joint 5^a is broken downwardly in folding, the pull of 75 the top covering upon the bow arm 7 and through the pin and slot connection upon the extension 6^b serves to balance the front extension and enable it to be moved back from one side into the position shown in 80 dotted lines, where it will be self-supporting and enable the operator to properly arrange the folds of the covering material preparatory to swinging the top back into its complete folded position.

85 The top covering between the standard and outrigger bow may be supported by a bow arm, as shown at 8, and if it be desired to have this bow arm positively guided, I may use a pair of links, such as shown in 90 Fig. 2 of the companion application filed of even date herewith.

In the form shown in Fig. 2 I pivot the intermediate portion of the bow arm 7^x to the upper end of the standard, as indicated 95 at α and connect its lower end to the link 6^x at β and connect its lower end to the link 6^x by a pin and slot connection γ or its equivalent.

In this form I prefer to pivot the front auxiliary bow arm 8^x to the outrigger bow 100 arm 5 and hold it positively in position by a distance piece or link 9 having one end pivotally connected to the front auxiliary bow arm and its rear end connected to a link 10, which link 10 connects the pivot pin at α 105 with the outrigger bow arm 5 at a point in advance of the lock joint 5^a.

110 It is obvious that if a five bow top is desired it is only necessary to support an extra bow directly upon the standard or continue

the standard upward to form the bow arm, as disclosed in Fig. 4 of the companion application filed of even date herewith.

What I claim is:

- 5 1. In a folding top, a main standard, an outrigger bow arm, a link pivotally connected respectively to said outrigger bow arm and to said standard, a cover supporting bow arm pivoted to said standard at a different height from the point of pivotal connection of the link to the standard and normally inclining rearwardly with relation to said standard, said link and said bow arm having a sliding connection between the end

of one of said elements and an intermediate 15 part of the other element.

2. In a folding top, a main standard, an outrigger bow, a link or member pivotally connected respectively to said outrigger bow and to the upper end of said standard and 20 having a part extending rearwardly of said standard and inclining upwardly, a cover supporting bow arm pivoted to said standard below the link pivot, and a sliding connection between said bow arm and the extended part of the link.

In testimony whereof I affix my signature.
MAX BUCH.
